UNITED STATES PATENT OFFICE

SYLVESTER M. SCHWELLER, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed October 26, 1927. Serial No. 228,919.

This invention relates to improvements in refrigerating apparatus and more particularly the cooling units or refrigerating elements intended for general use in refrigerators of the mechanically operated type.

It is one of the objects of the present invention to improve the construction of refrigerating elements of the finned duct type so that refrigerant will be conveyed in intimate contact to various parts of the fin for the efficient cooling of the entire fin and so that frost will not accumulate between adjacent ducts which cool the fin.

It is another object of the present invention to facilitate and reduce the cost of manufacture of refrigerating elements employing ducts and fins.

Further objects and advantages of the present invention will be apparent from the following description, reference being had to the accompanying drawing, wherein a preferred form of the present invention is clearly shown.

In the drawings:

Fig. 1 represents a side view, in cross section of a display case refrigerator equipped with the improved refrigerating element of the invention;

Fig. 2 is a top view of one section of the display case showing the refrigerating element in position therein;

Fig. 3 represents a side view of the refrigerating unit or element; and

Fig. 4 is a section of a portion of the unit or element taken on line 4-4 of Fig. 3.

Referring in detail to the drawings, the refrigerating element or cooling unit as shown in Figs. 3 and 4 comprises a header or tank 10 to which a refrigerating medium is supplied and by means of which the same is distributed to a series of cooling coils as herein-after described. The refrigerating medium, which may be, for example, sulphur dioxide, is led into the header preferably in liquid form through a pipe 11. A constant level of refrigerant is maintained in the header by means of a float valve, not shown. The vaporized refrigerant is led off from a space above the liquid level in the header by means of a pipe 12 which returns the refrigerant to the

compressing apparatus of the system which is not shown since it does not form a part of the present invention.

A series of cooling coils are connected to the header. These comprise a plurality of dependent ducts or loops of pipe 13 and 14 which are connected to the header in parallel below the liquid level thereof and which hang downwardly into the air which the unit is intended to cool. The ducts are preferably flattened to facilitate the attachment of fins and to increase the effective radiating surface of the ducts without necessitating the use of a large bore or increased refrigerant space in the pipe or duct. It will be observed that of the loops 13 each has one leg or branch 13" depending vertically from the header and substantially adjacent the vertical axis of the same and another leg or branch 13' also depending vertically from the header but offset laterally to a considerable extent. The loops 14 are similarly arranged with a leg 14" depending from the header substantially adjacent the vertical axis thereof and another vertically depending leg 14' offset laterally from said axis. The legs 13' and 13" of each of the loops 13 are connected by a horizontal branch portion and a like portion also connects leg portions 14' and 14" of loops 14. The loops are preferably arranged in sets, each set including a loop 13 and a loop 14. A plate or fin 15 consisting of a plane sheet of metal, preferably copper is interposed between the loops 13 and 14 of each set and secured in good thermal contact with each loop as by soldering. The loops are so arranged, as shown in Fig. 4 that the flat side of loop 13 faces the flat side of loop 14 thus defining a horizontal plane which is occupied by the fin. The fin consequently has loop 14 attached to its one side and loop 13 to the other side. In this manner the assembling of the fin and loops is facilitated. It is necessary only to insert a fin between the loops of a set and then solder same to the loops.

By the staggered arrangement of the branches of a set, refrigerant is conveyed to various portions of the fin so that the entire surface is cooled. By staggering the branches and by arranging the branches so that the next

adjacent branches are disposed on opposite sides of a fin, no pocket will be formed between adjacent branches and in this manner air can readily wipe over the surface of the fin next to the branches.

5 A tie-bar 16 suitably held in place as by soldering may be used to hold the bottoms of the finned loops in spaced relation, while the edges of the fins may be bent up and over, as 10 shown at 9, so as to strengthen the sheets of metal. The refrigerating element therefore provides a plurality of parallel channels or passages which guide the circulating air and cool the same. Due to such channels the efficiency of the refrigerating element is greater 15 than that of a cake of ice since in the latter the cooling effect is limited to the surfaces of the ice block lapped by the circulating air.

Figs. 1 and 2 show the refrigerating element of the invention disposed in a display case refrigerator. In such capacity its function is to replace the blocks of ice normally used for circulating and cooling the air.

The display case refrigerator comprises a 25 cabinet of substantially rectangular shape having a base and side walls 17. An interior lining 18 of enameled or painted metal is provided, while the walls are filled with suitable insulation 19 such as cork-board. A glass top 30 is provided comprising panes 20 separated by an insulating layer of air 21. A compartment is provided at each end of the case for housing the refrigerating elements. These compartments constitute chilling chambers for cooling 35 the air and circulating the same and are formed by the end and side walls of the display counter, a portion of the bottom of the case immediately beneath the refrigerating element, and a similar portion on the top of the cabinet. Insulated baffle walls 22 and 22' 40 are disposed inside the display case one at each end. These baffles are provided with openings or flues 23 at the top and similar openings 24 at the bottom to permit circulation 45 of air through both the food storage section of the display case and the chilling chambers. Glass sides (not shown) similar in structure to the top are provided for the front, and if desired, for part or all of the 50 rear of the case. As shown in Fig. 2 the chilling chambers containing the refrigerating elements may be provided with doors 25 of any suitable type, either sliding, or as illustrated, of the hinged type. Similar doors 55 may be disposed in the rear of the food compartment section of the display counter. The refrigerating elements are mounted in the chilling chambers by means of straps or hangers 26 as shown in Fig. 1, preferably clamped 60 around the header 10 and screwed to the inside top of the case. Shelves or trays for holding food or the like may be interposed between the top and bottom of the display case as indicated by the dotted line in Fig. 1 and 65 these should be arranged so as not to interfere

with free circulation of the air. This may be effected by suitably spacing the trays from the sides of the case or by constructing the shelves of screening or the like.

In the operation of the refrigerating elements and the display case, the refrigerating medium in the vertically dependent legs absorbs heat from the surrounding air and hence serves to cool and circulate the same. The fins on the legs aid in increasing the effective radiating surface of the loops and to direct the air currents. The circulation of air in the display case is substantially as follows: the warm air in the chilling chambers passes downwardly between the air channels formed by the fins on the dependent loops of the refrigerating elements. It is thus substantially cooled and flows downwardly and out into the body of the display case through openings 24. After absorbing the heat of the articles displayed within the display case the heated air travels upwardly and returns to the chilling chamber by way of the flues 23 in the baffles 22. Each chilling chamber produces its own range of air circulation, the currents of which meet substantially in the center of the case, thus insuring efficient cooling of the entire interior of the case.

While the form of embodiment of the invention as herein disclosed, constitutes a preferred form, it is to be understood that other forms might be adopted, all coming within the scope of the claims which follow.

What is claimed is as follows:

1. A cooling unit adapted to be placed in the path of cooling medium flowing thereover for cooling such medium, said unit including a heat absorbing plate or fin and refrigerant conduit means having a plurality of downwardly extending branch portions each thermally connected to one surface of the plate and conduit means thermally connected to the opposite surface of the plate.

2. A cooling unit adapted to be placed in the path of cooling medium flowing thereover for cooling such medium, said unit including a heat absorbing plate or fin and refrigerant conduit means having a plurality of branch portions each thermally connected to one surface of the plate and a conduit means having a plurality of branch portions each thermally connected to the opposite surface of the plate.

3. A cooling unit adapted to be placed in the path of cooling medium flowing thereover for cooling such medium, said unit including a heat absorbing plate or fin and refrigerant conduit means including a duct loop thermally connected substantially throughout its entirety to one surface of the plate and conduit means thermally connected to the opposite surface of said plate.

4. A cooling unit adapted to be placed in the path of cooling medium flowing thereover for cooling such medium, said unit in-

cluding a heat absorbing plate or fin and refrigerant conduit means including a duct loop thermally connected substantially throughout its entirety to one surface of the plate and another duct loop thermally connected substantially throughout its entirety to the opposite surface of the plate.

5. A cooling unit adapted to be placed in the path of cooling medium flowing there-over for cooling such medium, said unit in-
10 cluding a heat absorbing plate or fin and re-
frigerant conduit means including a plu-
rality of duct loops, said loops each having a
plurality of vertically extending branch
15 portions and a horizontally extending
branch portion connecting said vertically ex-
tending branch portions, at least two of the
branch portions of one of said loops being
thermally connected to one surface of the
20 plate and at least two of the branch por-
tions of another of said loops being ther-
mally connected to the opposite surface of
said plate.

6. A cooling unit adapted to be placed in
25 the path of cooling medium flowing there-
over for cooling such medium, said unit in-
cluding a heat absorbing plate or fin and re-
frigerant conduit means including a plu-
30 rality of duct loops, said loops each having
a plurality of branch portions spaced from
one another and from the branches of an-
other loop, the branches of one loop being
35 each thermally connected to one surface of
the plate and the branches of another loop
being each thermally connected to the oppo-
site surface of the plate.

7. A cooling unit adapted to be placed in
40 the path of a cooling medium flowing there-
over for cooling such medium, said cooling
unit including a plurality of heat absorbing
plates or fins and refrigerating means for
cooling said plates, said means including an
45 elongated header arranged transversely to
the plates, ducts connected with the header in
parallel circuit relation and extending longi-
tudinally with the plates, said ducts being
50 arranged in sets, and each set including a
plurality of branch portions thermally con-
nected to the surface of a plate and a plu-
rality of branch portions thermally con-
nected to the opposite surface of said plate.

8. A cooling unit adapted to be placed in
55 the path of a cooling medium flowing there-
over for cooling such medium, said cooling
unit including a plurality of heat absorbing
plates or fins and refrigerating means for
cooling said plates, said means including an
60 elongated header arranged transversely to
the plates, ducts connected with the header
in parallel circuit relation and extending
longitudinally with the plates, said ducts be-
ing arranged in sets, and each set including a
65 plurality of branch portions thermally con-
nected to the surface of a plate and a plu-
rality of branch portions spaced along the

plate and from the branches of the other duct
and thermally connected to the opposite sur-
face of the plate.

9. A cooling unit adapted to be placed in
70 the path of a cooling medium flowing there-
over for cooling such medium, said cooling
unit including a plurality of heat absorbing
plates or fins and refrigerating means for
cooling said plates, said means including an
75 elongated header arranged transversely to
the plates, a plurality of duct loops connected
with the header in parallel circuit relation,
said loops being arranged in sets, said sets
each including a plurality of loops spaced
80 from one another along the length of the
header and offset laterally from one another,
and each of said sets having at least three
downwardly extending portions thermally
connected with one of the plates.

10. A cooling unit adapted to be placed in
85 the path of a cooling medium flowing there-
over for cooling such medium, said cooling
unit including a plurality of heat absorbing
plates or fins and refrigerating means for
cooling said plates, said means including an
90 elongated header arranged transversely to
the plates, a plurality of duct loops connected
with the header in parallel circuit relation,
said loops being arranged in sets of plurality
of loops, the loops in the sets having sub-
95 stantially identical non-symmetrical shapes
and alternate loops being reversely turned
and offset laterally from one another, and
each of said sets having at least three down-
wardly extending portions thermally con-
nected with one of the plates.

11. A cooling unit adapted to be placed in
100 the path of a cooling medium flowing there-
over for cooling such medium, said cooling
unit including a plurality of heat absorbing
plates or fins and refrigerating means for
cooling said plates, said means including an
105 elongated header arranged transversely to the
plates, a plurality of duct loops connected
with the header in parallel circuit relation,
said loops being arranged in sets of plurality
of loops, the loops in the sets having sub-
110 stantially identical non-symmetrical shapes
and alternate loops being reversely turned
and offset laterally from one another, one of
the loops of a set having a plurality of down-
wardly extending branch portions thermally
115 connected with one surface of the plate and
the other loops having a plurality of down-
wardly extending branch portions thermally
connected with the opposite surface.

In testimony whereof I hereto affix my sig-
nature.

SYLVESTER M. SCHWELLER.
